UNITED STATES PATENT OFFICE

2,667,971

RESILIENT BUMPER STOP FOR SEPARATOR SCREENS

Leonard Johnson, Minneapolis, Minn., assignor
to Hart-Carter Company, Minneapolis, Minn.,
a corporation of Delaware

Application March 7, 1951, Serial No. 214,243

2 Claims. (Cl. 209—320)

1

My invention relates to grain separator construction and more specifically to improvements in grain separators utilizing sieves or screens which slope downwardly in the direction of flow and which are caused to oscillate rapidly to enhance the separating of the grains fed through the machine.

More particularly, my invention relates to separators having sloping screens, as above indicated, which partake of oscillatory movements transversely of the direction of flow, and has for its primary object the provision of novel means to prevent grain from flowing excessively toward one side or the other of said transversely oscillating screens.

Another object of my invention is the provision of a novel bumper or impact head which is adapted to be mounted in the path of oscillatory travel of one of said screens and engaged thereby when the screen moves to one of its limits of oscillatory movement, the impact between said screen and said head causing said screen to be jarred or jolted.

Still another object of my invention is the provision of means whereby a single bumper or impact head of the above type may be caused to impart a jarring action to a plurality of oscillating screens.

Another object of my invention is the provision of novel means for mounting a bumper or impact head of the above type and of means for adjusting the position of said impact head whereby the impact therebetween and the oscillatory screen associated therewith may be varied.

Still another object of my invention is the provision of a bumper or impact head and mounting therefor which is simple and inexpensive to produce, which is highly efficient in operation, and which is rugged in construction and durable in use.

The above and other highly important objects and advantages of my invention will become apparent from the following detailed specification, appended claims, and attached drawings.

Referring to the drawings which illustrate the invention, and in which like characters indicate like parts throughout the several views:

Fig. 1 is a view in perspective of a grain separator incorporating my invention;

Fig. 2 is an enlarged fragmentary section taken substantially on the line 2—2 of Fig. 1;

Fig. 3 is a fragmentary view in rear elevation on substantially the same scale as Fig. 2, some parts being broken away and some parts being shown in section; and

Fig. 4 is a fragmentary view partly in plan and

2

partly in section taken substantially on the line 4—4 of Fig. 3.

The separating machine illustrated is of the type generally known as a "dockage tester" and is adapted for testing samples of grain taken from a load to be tested. The machine includes a frame structure which comprises a base member 2 supported by legs or feet at the corners thereof, a pair of laterally spaced side frame elements 4 and 5, and a connecting top member 6. A plurality of grain separating elements in vertically spaced relationship includes a primary separating device 7, a secondary separator sieve or screen 8, and a pair of cooperating transversely oscillating separator screens 9 and 10. The separating device 7 and the screens 8-10, inclusive, in themselves do not constitute the invention, and being conventional in nature, it is not thought necessary to describe the same in detail. Hence, for the sake of brevity, it is thought that the above description will be sufficient.

Grain to be tested is fed into the conventional receiving hopper 11 of the machine and is carried over the several separating devices through the machine. The grain which goes through the several separating devices is transferred from an upper separator to one therebelow, and that which is carried to the delivery end of each separating device is discharged into a cooperating one of several receiving trays or pans 12, the smallest grains, namely those passing through the separator screen or sieve 10, being deposited in a receiver or tray 13 which rests upon the base 2. It will be noted, by reference to Fig. 1, that the several screens, particularly the transversely oscillating screens 9 and 10, slope downwardly in the direction of flow, the separating device 7 and the screen 8 being agitated by conventional means, not shown, to cause the grain to move thereover.

Means for mounting the screens 9 and 10 between the frame elements 4 and 5 comprises a plurality of lever-acting arms 14 which at their intermediate portions are mounted fast on rock shafts 15 that are journalled in bearing brackets 16 which in turn are secured to the side wall elements 4 and 5 by nut-equipped screws or the like 17. The upper ends of the lever-acting arms 14 are pivotally secured to mounting flanges 18 welded or otherwise rigidly secured to the frame 19 of the screen 9, as indicated at 20. The lower ends of the crank-acting arms 14 have pivotal connections 21 with mounting brackets or the like 22 secured fast to the frame 23 of the lower separator screen 10.

I provide mechanism for imparting oscillatory

movements to the screens 9 and 10 in directions transversely of the direction of flow of material over the screens which includes a drive shaft 24 which is journaled adjacent its opposite ends in suitable bearings in the side frame elements 4 and 5. At one end, the drive shaft 24 is provided with a pulley or sheave 25 which is adapted to be coupled to a suitable drive means such as a motor, not shown, by the means of suitable power transmission mechanism such as a drive belt or belts, not shown. An eccentric 26 is rigidly secured to the opposite end of the drive shaft 24 and drives a pitman arm 27 which at its free end is pivotally secured to the outer end of a crank arm 28 which extends inwardly through a slot 29 in the side frame member 5 and terminates in an enlarged head 30 which is rigidly secured to the adjacent rock shaft 15 by means of a set screw or the like 31. With particular reference to Figs. 2 and 3, it will be seen that rotation of the drive shaft 24 will impart oscillatory movements to the crank arm 28 in a vertical plane and consequent oscillatory movements of the screen-mounting arms 14 in directions transversely of the machine and of the direction of flow of the material over said screens 9 and 10.

If, for any reason, the screens 9 and 10 are not in a level condition transversely of the machine, grain moving thereon will tend to gravitate toward the low side or sides thereof often resulting in poor separation. To correct any such condition, I provide a bumper or impact head 32 preferably made from rubber or other resilient material and secured to the free end of mounting means such as a leaf spring 33 by means of a screw or the like 34. At its other end, the leaf spring 33 is bolted or otherwise rigidly secured to an inturned flange 35 integrally formed with the side frame element 5. The impact head 32 lies in the path of travel of a side portion of the frame 19 and is adapted to be impinged thereagainst upon oscillatory movement of the screen 9 in the direction of the impact head 32. The impact of the frame 9 against the head 32 causes the grain on the screen 9 to be jarred in the direction of the side frame element 5 so that, if the side of the screen 9 adjacent the side frame member 4 is lower than the opposite side thereof, the grain will tend to move away from the low side toward the longitudinal center of the screen. Means for moving the impact head 32 with respect to the limit of transverse oscillatory movement of the screen 9 to normal positions on either side of or at the said limit of movement comprises an adjustment means in the nature of a thumb screw 36 projecting through a suitable aperture in the intermediate portion of the leaf spring 33 and having thereon a head in the nature of an acorn nut or the like 37 which engages the inner surface of the side frame member 5. An adjustment nut 38 and a lock nut 39 are screw-threaded on the thumb screw 36 on opposite sides of the leaf spring 33. By unscrewing one of the nuts 38 or 39 away from the leaf spring 33 and tightening up of the other of the said nuts 38 or 39 against the leaf spring 33, the operator is able to adjust the normal position of the impact head 32 to a relatively fine degree. The resilient nature of the leaf spring 33 and that of the impact head 32, while having resistance sufficient to cause the grain to be appreciably jostled in the screens 9 and 10 toward the centers thereof, the spring 33 is sufficiently resilient to permit full oscillatory movement of said

screens 9 and 10 without damaging the mechanism for imparting said oscillations. The rigidity of the connecting arms 14 causes the impact between the screen 9 and the impact head 32 to be transferred to the screen 10 so that material which may have drifted to one side of the screen 10 will be jostled toward the longitudinal center thereof.

It should be understood that the impact head 32 and the resilient mounting therefor may with equal facility be mounted on the opposite side frame element 4 in the event that the screens 9 and 10 slope laterally in the opposite direction. It should also be appreciated that bumpers or impact heads may be installed on opposite side frame elements so that lateral slope in either direction could be quickly and easily corrected. It is possible to manipulate the screws 38 and 39 in a manner to cause the impact head 32 to be moved to a normal position laterally outwardly of the limit of oscillatory travel of the screen 9 in the event that the grain has no tendency to gravitate toward one side or the other of the screens 9 or 10. Obviously, adjustment of the head 32 toward the opposite side frame element 4 will increase the impact with which the screen 9 strikes the head 32, whereas adjustment of the head 32 in the opposite direction will decrease said impact.

My invention has been tested on a commercial basis and found to be completely satisfactory for the accomplishment of the objectives set forth; and, while I have shown a commercial embodiment of my improved device, it will be understood that the same is capable of modification without departure from the spirit and scope of the invention as defined in the claims.

What I claim is:

1. In a device of the class described, a supporting frame structure including a pair of laterally spaced side frame elements, a relatively flat separator screen disposed between said frame elements, said screen sloping downwardly in the direction of flow of material carried thereby, means mounting said screen for oscillatory movements transversely of the direction of flow, power driven mechanism for imparting said oscillatory movements to the screen, a rubber-like impact head, resilient means mounting said impact head in the path of oscillatory movement of the screen for movements into and out of one of the limits of oscillatory travel thereof, said resilient means comprising a leaf spring anchored at one end to one of said side frame elements, said impact head being secured to the free end of said spring, and adjustment screw means intermediate the ends of said spring and engageable with the adjacent side frame element for varying the normal position of the impact head with respect to said limit of oscillatory movement of the screen, whereby the impact between said screen and said head during oscillatory movement of the screen may be increased or decreased.

2. In a device of the class described, a supporting frame structure including a pair of laterally spaced side frame elements, a pair of relatively flat separator screens disposed between said frame elements, said screens sloping downwardly in the direction of flow of material carried thereby, means mounting said screens in vertically spaced parallel relationship for simultaneous oscillatory movements transversely of the direction of flow and in opposite directions, said last-mentioned means including lever-acting arms connecting said screens, power driven mechanism

for imparting said oscillatory movements to the screens, a rubber-like impact head, resilient means mounting said impact head in the path of oscillatory movement of one of the screens for movements into and out of one of the limits of oscillatory travel thereof, said resilient means comprising a leaf spring anchored at one end to one of said side frame elements, said impact head being secured to the free end of said spring and engageable with the adjacent side of said one of the screens, and adjustment screw means intermediate the ends of said spring and engageable with the adjacent side frame element for varying the normal position of the impact head with respect to said limit of oscillatory movement of said one of the screens, whereby the impact between said screen and said head during oscillatory movement of the screen may be increased

or decreased, said impact being transferred to the other of said screens through the lever-acting arms and causing material on said screens to be jarred in directions transversely thereof.

LEONARD JOHNSON.
